UNITED STATES PATENT OFFICE.

EUGENE D. C. BAYNE AND LAWRENCE A. SUBERS, OF CLEVELAND, OHIO.

MACHINE FOR COATING THE STRANDS OF A THREAD AND ALSO THE TWISTED THREAD.

No. 874,287.

Specification of Letters Patent.

Patented Dec. 17, 1907.

Application filed April 25, 1907. Serial No. 370,138.

To all whom it may concern:

Be it known that we, EUGENE D. C. BAYNE and LAWRENCE A. SUBERS, citizens of the United States, and residents of Cleveland, county of Cuyahoga, State of Ohio, have invented certain new and useful Improvements in Automatic Machines for Coating the Fibrous Strands of a Thread and also the Twisted Thread, of which we hereby declare the following to be a full, clear, and exact description, such as will enable others skilled in the art to which it appertains to make and use the same.

The objects of our invention are to provide automatically acting mechanism for preparing the thread from which an unwoven fabric may be formed having the qualities of great flexibility and tensile strength combined with perfect freedom from internal friction of the threads and their fibrous strands upon each other. To accomplish these objects the thread is first momentarily untwisted to separate the fibrous strands from each other, these strands are then coated with a non-fibrous coating of tenacious material such as india rubber which is dried upon them and they are then twisted together again to form a thread, this thread is then provided with an exterior coating of the same material which is also compressible and preferably vulcanizable and retains a tenacious surface by means of which the several threads of the fabric are attached together at the time of making the same. The coating when of the required thickness is compressed between forming rollers into a perfect cylindrical shape so that the fabric can be accurately made, and the layers thereof formed evenly and smoothly and to facilitate this end the threads are applied with pressure. The machine to accomplish these results comprises the automatically acting and momentarily untwisting device, a bath through which the separated fibrous strands are passed and in which they are held apart while passing therethrough, the drying blast for the coatings on the separate fibrous strands, a device for retwisting the strands to complete the thread devices, for coating the thread, for drying the coating, and for condensing and molding the coating thereon so as to prepare it for use in making the fabric. The machine also includes in its construction a rotatable cylinder containing a bath through which the momentarily separated fibrous strands are passed, and having perforated

heads through which the several strands are guided to hold them apart, while being coated.

Further features of the invention are shown such as the operating gears and shafts by means of which the cylinder is rotated to 60 momentarily untwist and retwist the thread, and to revolve the forming rollers by means of which the coated thread is pulled through the perforations in the cylinder heads, and the coating is shaped into cylindrical form. 65

The invention further comprises the combination and arrangement of parts and construction of the various details as hereinafter described, shown in the accompanying drawings and specifically pointed out in the 70 claims.

In the accompanying drawings, Figure 1 is a side elevation showing one side in vertical section of the complete device; Fig. 2 is a side view thereof; Fig. 3 is a transverse 75 section of the rotatable cylinder.

In these views 1 is the frame upon which is mounted the spool 2 upon which the thread 3 is wrapped, 4 is a cylinder containing a bath of the india rubber or other coating substance. This cylinder is provided with a head 5 and a bottom 6 perforated at 7 for the passage of the separated fibrous strands which compose the thread.

The thread is first passed through a central guide 8 and the several component strands are passed through the openings in the head and bottom, and are brought together again underneath the bottom and are retwisted by the rotation of the cylinder 80 4. The cylinder is rotated by means of the gears 9 and 10, and shaft 11, and intermediate gears 12 and 13 and shaft 14. After passing through the cylinder the coated strands are dried prior to retwisting by 95 means of an air blast passing through the drum 15 and the thread is held while twisting by means of the grooved rollers 16 and 17 below.

The thread is passed vertically after being 100 twisted through a bath 18 of similar coating material, and is then drawn through a reduced outlet nozzle 18' of the size required to provide the proper thickness of coating. The thread thus provided with an exterior 105 coating is then dried by passing it through an air blast 19, and finally the coating 20 is condensed and shaped into perfect cylindrical form by means of the forming rollers 16 and 17 which serve also as a feed device 110

- to pull the thread through the perforations in the cylinder. This process may be repeated as often as necessary to secure the proper thickness of coating required on the thread. The rollers are operated at the required speed relative to the momentarily untwisting and twisting speed of the cylinder by means of the shaft 21 and bevel gears 22, 23, and 24 and 25.
- 10 In order to easily introduce the fibrous strands of a thread consisting of two or more strands into the perforations in the cylinder and top and bottom plates easily the cylinder is vertically divided through the line of the 15 openings and made tight by means of the tongue and groove joints 25' in its sides, and the separate fibrous strands are introduced into their separate grooves before putting the parts together. The cylinder is supported upon the gear 9, and lugs 26 rest in sockets 27 thereon and supporting rings 28 form bearings for the upper and lower ends thereof. These rings are mounted upon the 20 brackets 29 upon the main supporting frame 25. 1, a ring 30 connected by means of rods 31 with the gear 9 encircles the top of the cylinder and keeps the divisions together. The perforations through which the fibrous strands pass have highly polished sides and 30 do not present any frictional resistance to their passage.

We believe ourselves to be the first to provide an automatic coating machine for the purpose of momentarily untwisting a thread consisting of two or more fibrous strands and coating the fibrous strands of such thread and retwisting the fibrous strands into a thread and coating the thread composed of the coated fibrous strands and to compress 40 and mold such coated thread into a perfect cylindrical form.

It is preferable that the thread and its component momentarily separated fibrous strands should be coated while in the vertical position, since by this means the coating is evenly applied and the strands and thread will be centrally located each in its coating.

Having described the invention what we 50 claim as new and desire to secure by Letters Patent is:

1. In a machine for the purpose described, an automatically acting device for momentarily untwisting and separating the fibrous strands of a thread, for coating the individual strands thereof while separated from each other, with a non-fibrous vulcanizable and tenacious material, for drying said coatings, for retwisting said strands to form a 55 thread, for forming an exterior coating thereon of similar material, for drying the same, and for compressing and molding said exterior coating into a true cylindrical form, substantially as described.
- 60 2. In a machine for the purpose described,

a device for momentarily untwisting the component fibrous strands of a thread, a bath for the untwisted threads, a device for drawing the strands therethrough and a retwisting device, substantially as described. 70

3. In a machine for the purpose set forth, a cylinder adapted to contain fluid coating material, a top and bottom plate therefor, said plates containing perforations, a central perforated guide and means for rotating said 75 cylinder, substantially as described.

4. In a device for the purpose of forming a coating upon a thread and upon each individual fibrous strand thereof, a rotatable receptacle for the coating material, through which 80 said strands in a separated condition, pass, means rotatable with the said receptacle for guiding and holding the said strands apart while passing therethrough and means for drying the several coatings on said strands, 85 the said holding and guiding means forming also, untwisting and retwisting means for said strands, and instrumentalities for preventing the twisted thread from turning, substantially as described. 90

5. In a machine for the purpose described, a cylinder having lines of perforations in its top and bottom plates, and separated longitudinally into two equal portions, the line of parting passing through the lines of said perforations, a perforated guide at one end of said cylinder, a gear detachably secured to one end of said cylinder, and supports in which said cylinder is rotatable, substantially as described. 100

6. In a machine for the purpose described, a thread untwisting device, a bath of non-fibrous compressible material through which the untwisted strands of said thread are passed, a device for holding apart said strands 105 while passing through said bath and devices for drying said strands and for retwisting them, for coating the twisted thread, and a pair of grooved rollers through which said coated thread passes and is shaped to a true 110 cylindrical form substantially as described.

7. In a machine for coating a fibrous thread with non-fibrous tenacious and compressible material, and for molding the coating into a true cylindrical form, a bath 115 through which said thread passes, a graduated tube through which the thread passes, an air blast for drying said coating, a pair of grooved rollers through which said coated thread passes, and means for rotating said 120 rollers in opposite directions, substantially as described.

In testimony whereof we hereunto set our hands this 22nd day of April, 1907, at Cleveland, Ohio.

EUGENE D. C. BAYNE.
LAWRENCE A. SUBERS.
